E. B. JOHNSON

BOILER CLEANER

Filed July 6, 1925

Patented Mar. 30, 1926.

1,578,318

UNITED STATES PATENT OFFICE.

EDWARD B. JOHNSON, OF ST. LOUIS, MISSOURI.

BOILER CLEANER.

Application filed July 6, 1925. Serial No. 41,785.

To all whom it may concern:

Be it known that EDWARD B. JOHNSON, a citizen of the United States of America, residing at St. Louis, State of Missouri, has 5 invented certain new and useful Improvements in Boiler Cleaners, of which the following is a specification.

The object of my invention is to make a boiler cleaner, particularly one which will 10 remove mud, scale, and prevent priming and which will prevent new scale from forming and gradually remove old scale. A further object is to make a boiler cleaner which will remove not only the sediment at the bottom 15 of the boiler, but the impurities and froth at the water line in the boiler. A still further object is to make a boiler cleaner that is made of few and simple parts that lend themselves readily to multiple production, 20 that can be easily and cheaply made and assembled, and placed in a boiler without perforating it further than it is normally. A still further object is to so shape the apertures or perforations in the pipes of my 25 device so as to prevent clogging with foreign substance.

With these and other objects in view, my invention has relation to certain novel features of construction and arrangement of 30 parts, as will be hereinafter more fully described, pointed out in the claim, and illustrated in the drawing, in which —

Fig. 1 is a fragmental sectional elevation of a boiler shell showing my device positioned therein.

Fig. 2 is an end elevation of the boiler shell showing diagrammatically the location of the tubes, the water line, and the positioning of my device.

Fig. 3 is a longitudinal sectional elevation of my skimmer, or device for removing the foreign substance that floats or remains in suspension in the froth of the boiling water.

Fig. 4 is a transverse sectional elevation 45 on the line 4—4 of Fig. 3.

Fig. 5 is a longitudinal, sectional elevation of a portion of my sediment collector.

Fig. 6 is a transverse sectional elevation on the line 6—6 of Fig. 5.

50 Numeral 7 designates the shell of a boiler having the blow-off opening 8, together with the cover 9. Numeral 10 designates the head, numeral 11 the tubes, and number 12 the water line.

55 My device consists of a shell 13, which is made of metal and is the fragment of a

hollow sphere in shape. Its edges are curved to conform to the curvature of the boiler shell 7 and it is positioned over the blow-off opening 8 and is of sufficient size 60 to completely cover said blow-off opening 8. The shell 13 is held in the shell 7 over the blow-off opening 8 gravitationally. Formed integral with the shell 13 is the L fitting 14 and the nipple fitting 15. The pipe 65 16 is placed in threaded engagement in the nipple fitting 15 and is of such length so that its top is submerged in the water a few inches. To the top of the pipe 16 in threaded engagement is secured the 70 skimmer 17, which consists of a pipe having the threaded hole 18 by which it is secured to the pipe 16, and having threaded ends into one of which, namely, the left one in Fig. 1, a plug is screwed, blocking that end 75 of the skimmer. Into the other end of the skimmer 17 is screwed the pipe 19. On the upper surface of the skimmer 17 intermediate its length is integrally secured a boss 20, having the aperture 21 formed 80 therein. The aperture 21 in establishing fluid communication between the skimmer 17 and the exterior of the boss 20 is made larger on its interior end and contracted on its exterior end.

Through the L fitting 14 in threaded engagement by means of the nipple 22, the sediment collector 23 is placed in fluid communication with the exterior of the shell 13. The sediment collector 23 consists of a pipe 90 24 having the feet 25 and the threaded opening at each end. In its lower surface, which is held in spaced relationship with the bottom of the shell 7 by means of the feet 25 is formed a boss 27 in which are formed holes 95 28 which are smaller at the exterior than they are on their interior ends. Numeral 29 designates a pipe with threaded ends, the left end of which is secured in threaded engagement with the right end of the sediment 100 collector 23, as best shown in Fig. 1. Numeral 30 designates a second sediment collector which is the exact duplicate of sediment collector 23 with the addition of a threaded hole 31 on its upper surface. Into this threaded hole 31 is screwed the pipe 32 which is of the same length as the pipe 16. Numeral 33 designates a second skimmer which is secured at its left end in threaded engagement to the pipe 19 and at its bottom to the pipe 32. The skimmers 17 and 33, together with the pipe 19, are maintained 110

2
in a state of parallelism relative the shell of the boiler about an inch and a half below the normal water level in the boiler. As many skimmers and sediment collectors may be added as is desired. For example in Fig. 1 a third sediment collector 34 and a third skimmer 35 are shown. The number of skimmers and sediment collectors that are used depend on the length of the boiler and the amount of dirt and scale that is to be removed. In a long boiler more will be used and where a great deal of dirt is to be removed, more will be used. The pipes 16, 32, and the pipe 36, etc., connecting the sediment collectors with the skimmers, pass between the tubes 11, as best shown in Fig. 2. The tubes prevent a diametral movement of my cleaner. When the boiler is under pressure the shell 13 is forced securely against the shell 7. When it is desired to clean the boiler, the cover 9 is removed and the pressure forces the light substance, together with the water, through the skimmers and the pipes, such as 16, 32, either directly as through the pipe 16, or indirectly as through the pipe 32, etc., to the shell 13 and on through the blow-off opening 8. The heavy sediment and scale that has been deposited at the bottom of the boiler is forced through the holes such as those in the sediment collector through piping system previously described, through the L fitting 14 into the shell 13 and out through the blow-off open-

ing 8. It will be seen that in this manner both the heavy material and the light material will be removed. By supporting the skimmers above the sediment collectors and having them in fluid communication, material from the skimmers may take the short path through such a pipe as 32 or 36 to the sediment collector, such as 23 or 30 to the blow-off opening 8. The apertures in the sediment collectors and the skimmers are tapered through the wall with a small opening on the outside in order to prevent the holes from becoming clogged. Any substance that can enter the hole will be able to go through the hole on account of the enlarged section passing inwardly.

What I claim and mean to secure by Letters Patent is:

The combination with a boiler of a cleaner therefor, said cleaner comprising a shell positioned over the blow-off opening of a boiler, a vertical and a horizontal pipe in fluid communication with said shell, sediment collectors connected in series in said horizontal pipe, a second horizontal pipe, a skimmer connecting said vertical pipe and said second horizontal pipe, additional skimmers connected in series in said second horizontal pipe, and additional vertical pipes placing all additional skimmers and sediment collectors in fluid communication.

In testimony whereof I affix my signature.

EDWARD B. JOHNSON.
